(57) CLAIM

The ornamental design for a container, as shown and described.

DESCRIPTION

FIG. 1 is a top perspective view of embodiment one, of a container, showing our new design.

FIG. 2 is a bottom perspective view thereof.

FIG. 3 is a side view thereof.

FIG. 4 is a top view thereof.

FIG. 5 is a bottom view thereof.

FIG. 6 is a cross-sectional view thereof, taken along line 6-6 of FIG. 3.

FIG. 7 is a top perspective view of the body thereof.

FIG. 8 is a bottom perspective view of the body thereof.

FIG. 9 is a side view of the body thereof.

FIG. 10 is a top view of the body thereof.

FIG. 11 is a bottom view of the body thereof.

FIG. 12 is a cross-sectional view of the body thereof, taken along line 12-12 of FIG. 9.

FIG. 13 is a top perspective view of the cap thereof.

FIG. 14 is a bottom perspective view of the cap thereof.

FIG. 15 is a side view of the cap thereof.

FIG. 16 is a top view of the cap thereof.

FIG. 17 is a bottom view of the cap thereof.

FIG. 18 is a cross-sectional view of the cap thereof, taken along line 18-18 of FIG. 15.

FIG. 19 is a top perspective view of embodiment two, of a container, showing our new design.

FIG. 20 is a bottom perspective view thereof.

FIG. 21 is a side view thereof.

FIG. 22 is a top view thereof.

FIG. 23 is a bottom view thereof.

FIG. 24 is a cross-sectional view thereof, taken along line 24-24 of FIG. 21.

FIG. 25 is a top perspective view of the body thereof.

FIG. 26 is a bottom perspective view of the body thereof.

FIG. 27 is a side view of the body thereof.

FIG. 28 is a top view of the body thereof.

FIG. 29 is a bottom view of the body thereof.

FIG. 30 is a cross-sectional view of the body thereof, taken along line 30-30 of FIG. 27.

FIG. 31 is a top perspective view of a cap thereof.

FIG. 32 is a bottom perspective view of the cap thereof.

FIG. 33 is a side view of the cap thereof.

FIG. 34 is a top view of the cap thereof.

FIG. 35 is a bottom view of the cap thereof.

FIG. 36 is a cross-sectional view of the cap thereof, taken along line 36-36 of FIG. 33.

FIG. 37 is a top perspective view of embodiment three, of a container, showing our new design.

FIG. 38 is a bottom perspective view thereof.

FIG. 39 is a side view thereof.

FIG. 40 is a top view thereof.

FIG. 41 is a bottom view thereof.

FIG. 42 is a cross-sectional view thereof, taken along line 42-42 of FIG. 39.

FIG. 43 is a top perspective view of the body thereof.

FIG. 44 is a bottom perspective view of the body thereof.

FIG. 45 is a side view of the body thereof.

FIG. 46 is a top view of the body thereof.

FIG. 47 is a bottom view of the body thereof.

FIG. 48 is a cross-sectional view of the body thereof, taken along line 48-48 of FIG. 45.

FIG. 49 is a top perspective view of the cap thereof.

FIG. 50 is a bottom perspective view of the cap thereof.

FIG. 51 is a side view of the cap thereof.

FIG. 52 is a top view of the cap thereof.

FIG. 53 is a bottom view of the cap thereof; and,

FIG. 54 is a cross-sectional view of the cap thereof, taken along line 54-54 of FIG. 51.

The broken lines in the figures illustrate the portions of the design that form no part of the claimed design.
